(57) **CLAIM**

The ornamental design for a door card for automobile or replica thereof, as shown and described.

DESCRIPTION

FIG. 1 is a front elevation view of a door card for automobile or replica thereof;

FIG. 2 is a left isometric view of FIG. 1;

FIG. 3 is a right isometric view of FIG. 1;

FIG. 4 is a top plan view of FIG. 1; and,

FIG. 5 is a bottom plan view of FIG. 1.

The dot-dash lines depict a boundary between claimed portions, which are inside the dot-dash lines, and portions that are not claimed, which are outside the dot-dash lines, of the door card for automobile or replica thereof.

The evenly spaced broken lines in the drawings illustrate portions of the door card for automobile or replica thereof that form no part of the claimed design.
